UNITED STATES PATENT OFFICE.

MORRIS LEVITAN, OF NEW YORK, N. Y.

DESIGN FOR AN ELECTRIC-LIGHTING FIXTURE.

Application filed September 28, 1925. Serial No. 14,924. Term of patent 3½ years.

To all whom it may concern:

Be it known that I, MORRIS LEVITAN, a citizen of the United States, residing at No. 868 Faile Street, borough of Bronx, city and State of New York, have invented a new, original, and ornamental Design for Electric-Lighting Fixtures, of which the following is a specification, reference being had to the accompanying drawing, forming a part thereof.

The figure shows a perspective view of my new, original, useful and ornamental design for an electric lighting fixture, as shown.

I claim:

The ornamental design for an electric lighting fixture, as shown.

MORRIS LEVITAN.
